AUTOMOBILE

Henry T. King, Detroit, Mich., assignor to Chrysler Corporation, Highland Park, Mich., a corporation of Delaware

Application May 11, 1955, Serial No. 35,937

Term of patent 14 years

(Cl. D14—3)

Fig. 1.

Fig. 2.

Fig. 3.

Fig. 1 is a perspective view of an automobile showing my new design;

Fig. 2 is a side elevational view thereof with the opposite side being similar to the one illustrated; and

Fig. 3 is a rear elevational view thereof.

The characteristic features of my design reside in the portions shown by means of full lines in the drawing.

I claim:

The ornamental design for an automobile, substantially as shown and described.
